UNITED STATES PATENT OFFICE.

CHRISTOPHER C. DENNY, OF BLAIR, NEBRASKA.

DESIGN FOR A WATERING-TROUGH.

SPECIFICATION forming part of Design No. 24,952, dated December 3, 1895.

Application filed March 8, 1895. Serial No. 541,048. Term of patent 34 years.

To all whom it may concern:

Be it known that I, CHRISTOPHER C. DENNY, a citizen of the United States, residing at Blair, in the county of Washington and State of Nebraska, have invented and produced a new and original Design for Automatic Watering-Troughs; and I do declare the following to be a full, clear, and exact description of the invention, such as will enable others skilled in the art to which it appertains to make and use the same, reference being had to the accompanying drawings, and to the letters of reference marked thereon, which form a part of this specification.

My design relates to watering-troughs; and the essential features thereof comprise a trough the ends of which are substantially in the form of a quadrant of a circle and one portion of the trough is in the form of a solid and the other portion is hollow, the solid portion projecting above the top of the hollow portion.

Figure 1 is a perspective view of a trough embodying my invention, and Fig. 2 is an end view.

In the drawings, A indicates the trough, one side of which, B, is straight or flat and

the other side, C, is curved and is joined thereto at the bottom at substantially a right angle. Each end F is substantially in the form of a quadrant of a circle, one of the straight sides of which joins the side B and the curved side joins the side C, and the other straight side forms the top of the trough. The base of the trough is slightly broader than its top, which causes the ends to slightly approach each other and gives the trough, when viewed from the outside, somewhat the appearance of an inverted truncated cone. The top of the solid portion D of the trough is at right angles to the side B and extends slightly above the top of the hollow portion E, and the inner end G of the solid portion forms the inner end of the hollow portion E.

I claim—

The design for a watering trough substantially as herein shown and described.

In testimony whereof I affix my signature in presence of two witnesses:

CHRISTOPHER C. DENNY.

Witnesses:

H. M. HOPEWELL,
A. E. THOMASON.
